COLLAR AND LIKE A

This invention relates to collars and like articles of apparel comprising a plurality of plies of fabric which are adhesively united by means of cellulose derivative yarns interwoven in one or more of said plies, and more particularly to men's collars of the folded type.

One of the objects of the invention is to provide a fold line of such character that it will give a narrow zone of relatively high flexibility where the collar will naturally tend to bend without imposing high stresses on the fabric of the collar.

A further object of this invention is to provide a collar of the character described which lends itself to manufacturing technique now available both in the weaving of the fabrics and in the manufacture of the collars. It is believed that this invention will provide a collar of this

Another object is to provide a collar type in which the fold-over portion of the collar, often called the "collar top" is formed in one piece with the band portion of the collar.

A still further object of the invention is to reinforce the collar band portion adjacent to the fold line.

The invention is illustrated conventionally in the accompanying drawing, in which:

Figure 1 is a plan view of a strip of the lining material from which the lining of the collar is cut, as indicated by the dash lines, and

Fig. 2 is a view of a completed collar laid out flat, with one of the outer plies and the lining ply partly broken away.

Referring now to the drawing, I indicates a strip of the lining material. This material, instead of being of the ordinary straight weave, is woven on a curve by what may be termed

is woven on a curve by what may be termed "conical weaving", and is of relatively narrow width, preferably only slightly wider than is required to cut one collar lining across the width.

5 of the strip, as indicated by the dash lines 2 in Figure 1. The lining, however, may be of greater width so that more than one collar lining may

be cut therefrom across the width thereof. However, for technical weaving reasons, the strip should preferably be kept to substantially the width of the weaving machine.

The lining comprises a plurality of bands preferably woven in one piece. The top band consists of warp threads 4 and filler threads 5 of cotton or other suitable material that will not be rendered cementitious in the subsequent treat-

(Cl. 2—131) *Interwoven in the warp are threads of a suitable cellulose derivative, such as cellulose acetate, which is capable of being made cementitious by treatment with a suitable solvent or by other known methods. The weave may be such that every third warp thread may be of cellulose derivative. This top band 3 constitutes the collar top portion of the lining and comes within the collar top portion 1 of the finished collar as seen in Fig. 2.*

Below the band 3 is a narrow band 4 of about $\frac{1}{8}$ " width, from which the cellulose acetate threads are omitted to provide a freely flexible fold line or zone. On referring to Fig. 2, it will be noted that in the collar this band is disposed along the fold line or zone which latter is indicated by the dot and dash line 5. In the completed collar the outer plies are unadhered to the lining along this fold line or zone.

The next lower band 10 of the lining is preferably of slightly greater width than the band 8, and of a tighter or closer weave, containing a greater number of cellulose derivative warp threads per inch than does the band 8. The band 10 may, if desired, be of double thickness. In the completed collar this band 8 lies within the collar band portion 11 of the collar immediately below and adjacent to the fold line or zone 9. The purpose of this band 10 is to reinforce and give greater stability to the collar, particularly to the collar band portion 11 thereof, just below the fold so as to minimize any tendency of the collar to turn outwardly or bulge at the fold under normal conditions of wear.

The succeeding band 12 is the collar band portion of the lining and is of the same, or of substantially the same weave and construction as the collar top portion or band 3 of the lining. This band 12, as will be seen on referring to Fig. 2, comes within the collar band portion 11 of the completed collar.

Below the band 12 there may be formed a band 13 from which the cellulose derivative threads are omitted, so as to leave the outer plies free from adhesion to the lining along the lower edge of the collar band portion 11 for convenience in attaching the collar to a shirt.

The outer or top and bottom plies 14 and 15 of the collar are made of any suitable fabric woven in the ordinary manner on a plain loom in contradistinction to the lining which, as above noted, is woven on a curve. The outer plies may be of shirting or other material commonly used in the manufacture of collars. In the case where the collar is attached to the shirt, these outer plies

may be made of the same material as the shirt.

In making the collar, the two outer plies and

the lining ply are cut to the proper shape. The

5 three plies are then assembled, with the lining

ply on the outside, and are stitched around on

all the edges, except the bottom edge of the band

portion, with a row of concealed stitches about

1/4" from the edge. The whole assemblage is

then turned inside out so as to bring the lining

10 on the inside between the outer plies. After the

collar has been turned, I may either close the

bottom edge to form a detached collar, or I may

leave said edge open in order that the collar

may be subsequently attached to a shirt. Upon

15 completion of the collar I adhesively unite the

plies together by any known method, depending

for the adhesion upon the latently adhesive prop-

erties of the cellulose derivative threads in the

lining.

20 My improved collar is of the kind generally

known as a "one piece" collar, that is, one in

which the fold-over portion or collar top 7 is

formed integral with the collar band portion

11, as distinguished from the usual fold-over

25 collar where the collar top and the collar band

are formed as separate parts and afterwards se-

cured together by stitching.

Various modifications in the details herein de-

scribed and shown may be made within the

20 spirit and scope of the invention.

This application is a continuation in part of an

application filed by me on June 13, 1935, Serial

No. 26,502.

What I claim is:

25 1. In a collar of the character described, the

combination with one or more straight-woven

plies of fabric, of one or more plies of curved-

woven fabric containing a non-uniform distri-

bution of cellulose derivative yarns in the warp,

40 said non-uniform distribution comprising the

omission of the cellulose derivative yarns in a

narrow region to form a fold line zone, and a

concentration of cellulose derivative yarns in

the band portion of the collar adjacent to said

45 fold line.

2. A collar of the fold over type in which the

collar top and the collar band portions are in-

tegral with each other and are adhesively united

except at the fold line, comprising outer plies

of straight-woven fabric, and a lining ply of fab-

ric yarns of cellulose derivative and yarns of

cotton extending on a curve in the direction of

the length of the collar, the cellulose derivative

yarns being omitted in the region of the fold

line and being of a closer weave immediately

below the fold line than at other parts of the 5

lining.

3. In a collar of the character described, the

combination with one or more outer plies of a

straight woven fabric, of a lining ply of a curved

woven fabric embodying latently adhesive warp 10

yarns extending on a curve in the direction of

the length of the collar, said latently adhesive

yarns being omitted along a narrow zone to form

an unadhered fold line.

4. A collar of the fold over type in which the 15

collar top and collar band portions are integral

with each other and are adhesively united ex-

cept in the region of a predetermined curved

fold line, comprising outer plies of straight woven

20 fabric, and a lining ply of woven fabric embody-

ing yarns of cellulose derivative and yarns of cot-

ton woven on a curve the curvature of which

extends in the direction of the length of the

collar and corresponds substantially to the curva-

ture of the fold line, the cellulose derivative yarns

25 being omitted in the region of the fold line.

5. In a one piece collar comprising a collar

top and band, the combination with one or more

outer plies of a straight woven fabric, of a

lining ply of a curved woven fabric embodying

latently adhesive warp yarns extending on a

curve in the direction of the length of the col-

lar, said latently adhesive yarns extending

throughout approximately the whole width of the

collar top and band and being omitted along a

25 narrow zone at the fold line to form an unad-

hered fold line.

6. In a one piece collar comprising a collar

top and band, the combination with one or more

outer plies of straight woven fabric, of one or

more lining plies of a curved woven fabric con-

taining a non-uniform distribution of a cellulose

derivative warp yarn extending on a curve in

the direction of the length of the collar, said

cellulose derivative yarn extending throughout

45 approximately the whole width of the collar top

and band and being omitted in a region to form

a fold line zone and concentrated in the band

portion of the collar adjacent the fold line.

PAUL METZGER.
